LATERAL ROLLER TRACK GUIDE

William L. Deysher, 34 Tamalais Ave., San Anselmo, Calif., and Verne C. Coker, 712 Alice St., Novato, Calif.

Filed Sept. 20, 1960, Ser. No. 57,201
11 Claims. (Cl. 305—28)

This invention relates generally to the tracks of bulldozers, tractors, and similar machines and, more specifically, the instant invention pertains to an attachment for a machine of this type, and comprises a continuation-in-part of my co-pending application bearing the same title, Serial No. 732,693, filed May 2, 1958.

As will be seen, as the present specification progresses, the attachment, according to this invention is designed for use on tracks of the endless type, and has as its primary purposes the prevention of lateral displacement of the track from its proper position.

In many types of operations, as for example, those performed on hillsides by machines of the type referred to above, great lateral pressure is exerted on the tracks which frequently results in causing the track flanges to engage against the flanges of the track rollers. In other words, if lateral pressure is exerted in one direction upon the track, it will tend toward lateral displacement, so that one track flange thereof will be caused to bear frictionally against an adjacent track roller. Under these conditions, the track suffers considerable wear whereby the effective life of the track is reduced to a high degree below that which is desirable. Furthermore, excessive lateral pressure sometimes causes the tracks to slide off the associated support assembly, and this results in considerable lost time during the required repair period.

As has been stated above, one of the principal objects of this invention is to provide means that will prevent the track roller flange from engaging the adjacent track flange when relative lateral displacement of the track and the associated rollers tends to arise. Such lateral pressure may occur, it should be noted, not only when operations are being performed on hillsides and other side grades, but also during the ordinary turning of a tractor or bulldozer.

A further object of this invention is to provide a device of the type clearly described supra, the device being comparatively inexpensive to manufacture, non-complex in construction and assembly, and durable in use.

Another object of this invention is to provide a device of the character stated which will be so formed as to be incorporated in conventional tractors presently in use, the incorporation of the device being accomplished with but a minimum expense.

A still further object of this invention is to provide a means of the type described which will not interfere in any way with normal running of the track upon its associated track rollers. The means, according to the present invention, is so designed, in fact, as to be ordinarily disposed substantially out of contact with the adjacent surfaces of the track, contact between the guide and the track being produced only when the aforementioned lateral pressures come into being.

Still another object of this invention is to provide an attachment of the type referred to above which is so designed as to engage the track flange before the track flange can come into engagement with adjacent rollers.

This invention contemplates, as a still further object, the provision of a track guide attachment which does not come into engagement with a track flange except upon the occurrence of a lateral pressure thereon, and wherein only a minimum friction occurs between the engaging surfaces of the guide and track flange upon the occur-

2

rence of lateral pressure, whereby the track flange does not undergo any appreciable wear.

Other and further objects and advantages of the instant invention will become more evident from a consideration of the following specification when read in the light of the annexed drawings, in which:

FIGURE 1 is a fragmentary side elevational view of a machine employing a conventional endless type track, and illustrating the attachment according to this invention in its environment;

FIGURE 2 is an enlarged detail cross-sectional view of the roller track guide attachment constructed in accordance with this invention, FIGURE 2 being taken substantially on the vertical plane of line 2—2 of FIGURE 1, looking in the direction of the arrows;

FIGURE 3 is an enlarged side elevational view, partly in section, FIGURE 3 illustrating the relationship between track rollers, the track flanges, the track per se, and the roller track guide attachment constructed in accordance with this invention; and

FIGURE 4 is a top plan view, partly in cross-section, and again illustrating the association of the roller track guide with other component elements of a conventional machine using an endless type track, FIGURE 4 being taken substantially on the horizontal plane of line 4—4 of FIGURE 3, looking in the direction of the arrows.

Referring now more specifically to the drawings, reference numeral 10 (see FIGURE 1) designates, in general, a conventional machine of the type referred to above.

The machine 10 is adapted to be moved by means of endless type tracks 12 or endless treads which are suitably mounted on opposite sides of the machine 10. The track 12 includes a plurality of links 14 disposed in end-to-end relation, and with the adjacent end of each pair of links pivotally connected together by means to be described below. Each of the links 14 is integrally formed with at least one transversely-extending ground-engaging cleat 16.

Referring now in particular to FIGURE 2 of the drawings, it is seen that each of the links 14 includes a substantially rectangular tread portion 18 which is integral with the cleat 16 and from which the latter depends. Rigidly secured to each tread portion 18 and extending longitudinally thereof are a plurality of substantially up-

right rectangular laterally-spaced and substantially parallel track flanges 20. The flanges 20 adjacent each end thereof are apertured to receive a connecting pin and bushing 22, 24, respectively, whereby each link 14 is pivotally connected at each end with an immediately adjacent link. This is conventional in this art.

The machine 10, on opposite sides thereof, is provided with a drive sprocket 26 carried by an axle (not shown) journaled for rotation in bearing blocks 28. The bearing blocks 28 rest on the top wall 30 of a substantially hollow, elongated rectangular track roller frame 32 which includes, a pair of elongated, laterally-spaced, and substantially rectangular side walls 34, 36. A normally horizontal bottom wall 38 integrally connects the lower ends of the side walls 34, 36.

The above description pertaining to the track roller frame 32 is conventional in this art, but it should be here noted that each track 12 is provided with a second track roller frame 32' disposed inwardly of the track roller frame 32, elements of the innermost form of the roller

track frames being identified in the drawings by the same reference numerals, but to which has been assigned a prime mark to differentiate one from the other.

The side walls 36, 36' are maintained in spaced, substantially parallel relationship with respect to one another by means of conventional cross straps 40 which extend therebetween and are rigidly secured thereto. As is seen in FIGURES 1 and 4, the cross straps 40 are longi-

tudinally spaced with respect to the side walls 36, 36'. This, too, is conventional in machines of this type.

Also conventional in this art is the inverted substantially L-shaped rock guard 42, 42', the rock guards 42, 42' having foot portions 44, 44' fixedly secured to the bottom walls 38, 38' by means of bolts 46.

Journals 48 are fixedly secured to the foot portions 44, 44' and support the opposed ends of a shaft 50 having a pair of track rollers 52 integral therewith, each of the track rollers 52 frictionally engaging, respectively, the upper ends of each of the track flanges 20. As is seen in the drawings, each of the track rollers 52 is provided with circumferential flanges 54 which are disposed immediately adjacent the upper ends of each of the track flanges 20. This is also conventional structure in this art.

As has been stated above, one of the primary objects of this invention is to provide means for preventing engagement of the upper ends of the track flanges 20 with the track roller flanges 54 when a lateral pressure is exerted upon the track 12. To this end, this invention comprises an attachment which is designated, in general, by reference numeral 56. The attachment 56 includes diametrically-opposed, oppositely outwardly-bowed tongues 58 (see FIGURES 2 and 4) constituting extensions upon the upper end of a vertically-disposed sleeve 60. Formed in the tongues 58 are diametrically-opposed slots 62, in which is received one of the straps 40.

The tongues 58 serve a stabilizing function, that is, as will presently appear, they cooperate in holding the sleeve 60 in its proper, normally-vertical position. This will be described in detail hereinafter.

At the base of each of the tongues 58, the sleeve 60 is provided with shoulders 64, and as is shown in FIGURE 2, there is provided an upper cap plate 66 formed as a flat, circular member, having diametrically-opposed ears 68 supported upon the shoulders.

Screws 70 or equivalent fastening means are extended through the ears 68 into the shoulders 64 to fixedly secure the cap plate 66 in position extending across the upper portion of the sleeve 60, at the base of the stabilizing tongues 58 immediately below the strap 40.

Integrally formed upon diametrically-opposed portions of the sleeve 60, at the lower end thereof, are laterally outwardly-extending support bars 72 extending in coaxial alignment and projecting radially from the sleeve 60. Gussets 74 are formed integrally with the support bars and sleeve to reinforce the construction, and in the outer ends of the bars 72 axial, threaded openings 76 are formed, aligning with smooth-walled openings 78 formed in the rock guards 42, 42' of the leg portions 80, 80' thereof. Bolts 82, 84 extend through the openings 78 and are threaded in the axial recesses 76. The bolt 82 has a grease fitting 86 through which lubricant can be forced under pressure to pass through a grease passage 88 into a chamber 90 surrounding a vertical stem 92 which extends axially within the sleeve 60.

It will be seen that when the bars 72 are secured to the foot portions 80, 80' of the rock guards 42, 42', with the slots 62 receiving one of the straps 40, the sleeve 60 will be held in a vertical, immovable position relative thereto.

At its upper end, the stem 92 is journalled in a tapered roller bearing 94, the stem 92 having a cap 95 secured to the upper end thereof by means of bolts 98. As is seen in FIGURE 2, the bolts 98 are threaded into longitudinal recesses formed in the upper end of the stem 92 to hold the bearing 94. Suitable shims (not shown) could be interposed between the plate or cap 95 and the bearing 94 to permit adjustment of the latter.

The stem 92 is formed in its lower end with a collar 100, defining a shoulder 102 immediately above which is a tapered roller bearing 104 separated from the shoulder 102 by one or more shims 106. A grease seal 108 is secured by screws 110 to the undersides of the bars 72 in position extending about the collar 100.

Integral or otherwise made rigid with the collar 100 of the stem 92 is a guide roller 112, rotating in a horizontal plane. As is seen in the several figures of the drawings, the guide roller 112 is so positioned as to be disposed between the adjacent sides of each of the track flanges 20 in close proximity thereto, but slightly spaced therefrom.

This completes the description of the attachment.

Ordinarily, there is no attachment such as is designated at 56 herein. Therefore, if lateral pressure should be caused to exert itself in the track 12, relative to the track roller 52, the tread 18 tends to be displaced laterally with respect to the rollers 52 and their respective flanges 54. Assuming, for the sake of example, that a section of the track 12 is tending to move laterally to the left, as viewed in FIGURE 2, the left-hand one of the flanges 20, in this figure of the drawings, would be brought to bear forcibly against the inner face of the left-hand track roller flange 54, shown in the same figure of the drawings. This causes great and rapid wear upon the tracks 12 and often causes them to be forced off the roller assembly completely.

It follows that during normal operation of the machine 10, when there are no lateral pressures tending to displace the tread section portions 18 laterally with respect to the rollers 52 and their respective flanges 54, the flanges 54 will be out of contact with the flanges 20 and the roller 112. There is no wear in these circumstances on the flanges 20. However, when the lateral pressure, as for example, to the left in FIGURE 2 occurs, the right-hand flange 20, in conventional constructions, will come to bear against the right side of the roller 112, viewing these components as in FIGURE 2. This will occur before the left-hand flange 20 can come to bear against the left-hand flange 54 of the left-hand roller 52 in FIGURE 1.

Immediately upon contact of the roller 112 with the right-hand flange 20, and since the flanges 20 are traveling in the direction of its length, the roller 112 will begin to turn about the axis defined by the stem 92. There is no appreciable wear, accordingly, on the right-hand flange 20 because it is kept out of contact with the immediately adjacent roller flange 54 and friction between the engaging members is held to a minimum, due to the free rotation of the roller 112 caused by the longitudinal movement of the engaging flange 20.

The attachment as constructed in accordance with the present invention may be incorporated in existing tractors, bulldozers, and similar machines using endless type tracks, and in the instant case the attachment has been shown in conjunction with a conventional tractor. It will be appreciated that the attachment may be placed in use on machines of this type and a very low expense incurred, since no modification or re-design of any kind is required in the conventionally-existing machines other than, perhaps, the boring of the openings 78 in the rock guards 42, 42'.

The sizes of the attachment would vary according to the different makes and types of machines upon which it is intended to secure the same. Further, there may be certain modifications that do not depart from the spirit and scope of the invention as claimed.

Still further, it will be understood that the attachment 56 may be used in any desired number, and may be employed wherever desired, at such distances apart as will insure that the tread flanges 20 will, at all times, be kept completely or substantially out of contact with the track roller flange 54, regardless of the amount of lateral pressures tending to relatively laterally displace the tread portions 18.

It is believed apparent that the invention is not necessarily confined to specific use on tractors, referred to above, since it may be utilized for any purpose to which it may be suited. Nor is the invention to be necessarily limited to the specific construction illustrated and described, since such construction is only intended to be illustrative of the principles, it being considered that the invention comprehends any minor change in construc-

tion that may come within the scope of the appended claims.

What is claimed is:

1. In a vehicle of the type having a ground-engaging endless tread, the combination of a support structure for the vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of said pair thereof with said roller flanges, respectively, of each pair of said rollers being juxtaposed and normally laterally spaced from each remote side of said pair of tread flanges, a tread guide limiting the lateral displacement of said tread relative to the support structure and said rollers to an extent that would fixedly bind a tread flange against an adjacent roller flange, comprising: a support sleeve; means for mounting the same on said support structure; a stem extending within said sleeve; and a guide roller carried by the stem and disposed between said pair of tread flanges, so as to engage one of said tread flanges and thereby limit the tread against substantial lateral movement whenever said tread tends to be displaced in a lateral direction toward said track roller flange adjacent the other of said tread flanges.

2. In a vehicle of the type having a ground-engaging endless tread, the combination of a support structure for the vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of said pair thereof with said roller flanges, respectively, of each pair of said rollers being juxtaposed and laterally spaced from each remote side of said pair of tread flanges, a tread guide limiting the lateral displacement of said tread relative to the support structure and said rollers to an extent that would frictionally bind one of said tread flanges against an adjacent roller flange, comprising: a support sleeve; bars projecting laterally and outwardly from opposite sides of said sleeve and fixedly connected to portions of said support structure extending at opposite sides of said sleeve, thus to mount said sleeve upon said support structure; a stem extending within said sleeve; a guide roller carried by said stem and disposed between said pair of tread flanges, so as to engage one of said tread flanges and thereby limit the tread against substantial lateral movement whenever said tread tends to be displaced in a lateral direction relative to said track roller flange immediately adjacent the other of said tread flanges.

3. In a vehicle of the type having a ground-engaging endless tread, the combination of a support structure for the vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of said pair thereof with said roller flanges, respectively, of each pair of rollers being juxtaposed and laterally spaced from each remote side of said pair of tread flanges, a tread guide limiting the lateral displacement of said tread relative to the support structure and said roller flanges to an extent that would frictionally bind one of said tread flanges against the immediately adjacent roller flange, comprising: a support sleeve; means securing said support sleeve on said support structure; a stem journaled within said sleeve; and a guide roller rigid with said stem below said sleeve and disposed between said tread flanges in position to rotate on an axis perpendicular to the axes on which the respective track rollers rotate, said guide roller being disposed in position to engage either one of said tread flanges against substantial lateral movement whenever the tread flanges tend to be displaced in a lateral direction relative to said track roller flanges.

4. In a vehicle of the type having a ground-engaging

endless tread, the combination of a support structure for said vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of said pair thereof with said roller flanges, respectively, of each pair of said rollers being juxtaposed and laterally spaced from each remote side of said pair of tread flanges, a tread guide limiting the lateral displacement relative to said support structure and said roller flanges to an extent that would frictionally bind one of said tread flanges against an adjacent roller flange, comprising: a support sleeve; means mounting said support sleeve on said support structure; a stem journaled within said sleeve; and a guide roller rigid with said stem below said sleeve and disposed between said tread flanges in position to rotate on an axis perpendicular to the axes on which the respective track roller flanges rotate, said guide roller being disposed in position to engage either one of said tread flanges to prevent substantial lateral movement whenever the tread tends to be displaced in a lateral direction relative to said track roller flanges, said stem being supported within said sleeve against axial displacement relative to said sleeve.

5. In a vehicle of the type having a ground-engaging endless tread, the combination of a support structure for the vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of said pair thereof with said roller flanges, respectively, of each pair of rollers being juxtaposed and laterally spaced from each remote side of said pair of tread flanges, a tread guide limiting the lateral displacement of said tread relative to the support structure and rollers to an extent that would frictionally bind a tread flange against an adjacent roller flange, comprising: a support sleeve; means mounting said support sleeve on said support structure; a stem journaled within said sleeve; and a guide roller rigid with the stem below the sleeve and disposed between said pair of flanges in position to rotate on an axis perpendicular to the axes about which the respective track rollers rotate, said guide roller being disposed proximate to but spaced from said track flanges and in position to engage either one of said tread flanges under substantial lateral movement of said tread whenever said tread tends to be displaced in a lateral direction relative to said track roller flanges, said stem being supported within said sleeve against axial displacement relative to said sleeve, said means mounting said sleeve on said support structure including bars rigid with and projecting radially outwardly from diametrically-opposed portions of said sleeve, said bars being fixedly connected to said support structure, one of said bars having a grease passage, said stem being spaced from the wall of said sleeve to define a lubricant chamber, said passage opening into said chamber.

6. In a vehicle of the type having a ground-engaging endless tread, the combination of a support structure for the vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of said pair thereof with said roller flanges, respectively, of each pair of rollers being juxtaposed and laterally spaced from each remote side of said pair of tread flanges, a tread guide limiting the lateral displacement of said tread relative to the support structure and rollers to an extent that would frictionally bind one of said tread flanges with said track rollers to an extent that would frictionally bind a flange against an adjacent roller, comprising: a support sleeve; means

mounting the same on said support structure; a stem journaled within said sleeve; and a guide roller rigid with the stem below said sleeve and disposed between said pairs of tread flanges in position rotating on an axis perpendicular to the axes about which the respective track roller flanges rotate, said guide roller being disposed proximate to but spaced from said tread flanges and in position to engage either one of said pair of flanges against substantial lateral movement whenever said tread tends to be displaced in a lateral direction relative to said track rollers, said stem being supported within said sleeve against axial displacement relative to said sleeve, said means mounting said sleeve on said support structure including bars rigid with and projecting radially outwardly from diametrically-opposed portions of said sleeve, said bars being fixedly connected to said support structure, one of said bars having a grease passage, said stem being spaced from the wall of said sleeve to define a lubricant chamber, said passage opening into said chamber, said sleeve mounting means further including extensions on the upper end of said sleeve having slots receiving an overhead portion of said support structure to which said sleeve is connected.

7. In a vehicle of the type having a ground-engaging endless tread, the combination of a support structure for the vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of a pair thereof with said roller flanges, respectively, of each pair of rollers being juxtaposed and laterally spaced from each remote side of said pair of tread flanges, a tread guide limiting the lateral displacement of said tread relative to the support structure and roller flanges to an extent that would frictionally bind a tread flange against an adjacent roller flange, comprising: a support sleeve; means mounting said support sleeve on said support structure in a normally upright position; said sleeve having an internal chamber at the lower end thereof; a stem journaled within said sleeve; a guide roller rigid with said stem below said sleeve and disposed between said pair of flanges in position to rotate on an axis perpendicular to the axes about which the respective track roller flanges rotate, said roller being disposed in position to engage either one of said tread flanges under substantial lateral movement whenever said tread tends to be displaced in a lateral direction relative to said track roller flanges and roller bearings interposed between said sleeve and said stem at opposite ends of said chamber to provide a journal for said stem within said sleeve.

8. In a vehicle of the type having a ground-engaging endless tread, the combination of a support structure for the vehicle adjacent said tread, said tread being formed with a pair of laterally-spaced tread flanges, and a plurality of pairs of track rollers, each roller of each pair thereof having a circular flange formed thereon, one roller of each pair of said rollers engaging, respectively, one of said tread flanges of said pair thereof with each roller flange, respectively, of each pair of rollers being juxtaposed and laterally spaced from each remote side of said pair of tread flanges, a track guide limiting the lateral displacement of said tread relative to the support structure and roller flanges to an extent that would frictionally bind one of said tread flanges against an adjacent roller flange, comprising: a support sleeve; means mounting said support sleeve on said support structure; a stem

extending within said sleeve; and a guide roller carried by said stem and disposed between said pair of flanges, so as to engage one of said pair of flanges and thereby limit said tread against substantial lateral movement whenever said tread tends to be displaced in a lateral direction relative to said track roller flanges, said guide roller being closely spaced from the respective pair of flanges, a distance such as to cause said guide roller to be engaged by one flange before the other flange can engage the immediately adjacent track roller flange.

9. In a vehicle of the type including a ground-engaging endless tread for the vehicle, the combination of a support structure for the vehicle adjacent said tread, said tread including generally flat, pivotally-joined portions each of which is formed with a pair of tread flanges spaced laterally from each other and inwardly from the respective side edges of said portions, and a plurality of pairs of track rollers, each roller of each pair thereof having a circular flange thereon, said rollers rotating on axes parallel to the plane of said portions and peripherally contacting, respectively, said tread flanges, said roller flanges of each pair of rollers being disposed adjacent, respectively, the remote sides of said pair of said tread flanges in spaced relation relative thereto, a tread guide for limiting lateral displacement of said tread portions relative to said support structure and said rollers to an extent that would frictionally bind one of said tread flanges against its immediately adjacent roller flange, comprising: a guide roller disposed in the space between said tread portion flanges in close proximity at its periphery to said last-named flanges, for confinement of each tread flange between said guide roller and the adjacent tread roller flange; and means providing a mounting of said guide roller on said support structure, said guide roller being freely rotatable on said means on an axis normal to that portion of said tread disposed immediately therebelow, said tread flanges being so positioned with respect to said guide roller so as to effect engagement with one of said tread flanges with said guide roller when said tread portion tends toward lateral displacement, and before engagement of the other of said tread flanges with said flange of said track roller immediately adjacent thereto.

10. In a vehicle of the type including a ground-engaging endless tread, the combination of claim 9, and said track rollers being symmetrically disposed with respect to said guide roller and the opposed remote sides thereof, the distance between said guide roller peripheries and each track roller being greater than the width of said tread flanges therebetween to an extent effective to space said guide roller and said track roller flanges outwardly from the sides of said tread flanges disposed immediately adjacent thereto when the tread is in a centered position relative to the support structure as distinguished from a laterally-displaced position.

11. In a vehicle of the type including a ground-engaging endless tread, the combination of claim 10, and said track roller flanges are normally disposed in spaced relation relative to the tread portion flanges at all times and away from said guide roller, and the latter being normally out of contact with either of said pair of flanges on said tread portion.
